UNITED STATES PATENT OFFICE.

ERNEST O. NORBERG, OF PATCHOGUE, NEW YORK.

AMUSEMENT APPARATUS.

Application filed March 29, 1923. Serial No. 628,676.

To all whom it may concern:

Be it known that I, ERNEST O. NORBERG, a subject of the King of Sweden, and a resident of Patchogue, county of Suffolk, and 5 State of New York, have invented a new and useful Improvement in Amusement Apparatus, of which the following is a specification.

The object of my invention is to provide 10 an amusement apparatus which may be used at resorts or elsewhere to afford persons amusement by playing a game which simulates baseball so that several persons may play at once and each in competition with 15 all the others. This object is accomplished by my invention, one embodiment of which is hereinafter more particularly set forth.

For a more detailed description of my invention, reference is to be had to the accompanying drawings, forming a part hereof, 20 in which—

Figure 1 is a side elevation of an apparatus embodying my invention.

Figure 2 is a plan view of one section of 25 the same, it being understood that other sections are identical therewith.

Figure 3 shows a detail of construction involving the controller which is operated by the player.

30 Figure 4 is a diagrammatic view showing the electrical connections for one panel.

Figure 5 shows a portion of the ball projecting mechanism of the apparatus.

Figures 6 and 7 are side and plan views 35 of the figure moving parts of the apparatus, and.

Figure 8 shows an escapement for releasing the figure.

Throughout the various views of the 40 drawings, similar reference characters designate similar parts.

My improved apparatus 1 contains several panels 2, one of which only will be described as it is understood that others are duplicates 45 thereof and as many may be put in line or otherwise, as required. Each panel 2 has an actuating lever 3 which may take the form of a bat and preferably does so, which is pivoted at 4 on uprights 5 that rise from a

50 table 6 which is separated from a second table 7 so that an aisle 8 is had where an attendant may move to attend to the game and collect fees and perform any other duties incident to his position. The aisle 8 may be 55 closed at each end by suitable swinging gates 9, or in any other suitable way.

The bat or lever 3 has one end 10 which may be struck by a player and pressed downwardly towards the table 6 and when so pressed the other end is elevated and will 60 pull a cord 11 which runs over a number of pulleys 12 to the lever 13 which is pivoted at 14 between uprights 15 on the floor of a box 16 which preferably has a glass front 17 through which the contents may be 65 viewed. This box 16 is mounted on the front of the table or cabinet 7 and near the top thereof and in a position where it may be viewed by the player. The lever 13 is held in an inclined position, as shown 70 in Figure 5, by means of a coil spring 18 which has one end secured to a bracket 19 secured to the bottom of the box 16 and the other end to an eyelet or other suitable means, on this lever, so that when the cord 75 11 is pulled the spring 18 is put under tension and this cord is pulled against the tension of the spring. The position of the parts is such that the lever 13 is inclined from the horizontal, as shown, under normal conditions and the lower end of this lever carries a ball 20 which is thrown upwardly when the string 11 is suddenly pulled. This string is given a sudden pull when the end 80 10 of the lever 3 is struck by the hand of the player. The force with which the ball 20 will be projected will depend on the force with which the part 10 is struck, as above described. In the box 16 are two guides 21 and 22 which are flared slightly and at their 85 lower ends are normally closed by the spring pressed trap 23 which is so arranged and disposed, as will be described below, that it will fly open and permit the ball 20 to fall on the lever 13 and close immediately after the 90 ball leaves it. The guides 21 and 22 are flared more or less, as desired, so as to make more or less space to receive the ball 20 when it is projected upwardly, according to the 95 desires of the designer of the apparatus. The depth of the box 16 is such that the ball 20 can move freely therein, that is the depth between the glass 17 and the side or back opposite is a little more than the diameter 100 of the ball.

The trap 23 is attached to a spindle 24 which is fixed thereto and has at its inner end a disc 25 which carries two escapement pins 26 and 27. One side of the disc 25 has a counter-weight 28^a which will keep the flap 23 in a horizontal position under normal conditions and the pin 27 in engage- 105 110

ment with a tooth of the ratchet 28 which turns freely on the fixed, hollow shaft 29 that has its lower end secured in a disc 30 that is fixed to a crossing 31 of the table 7. 5 The upper end of the shaft 29 has a fixed disc 32 mounted thereon and also a disc 33 which may be turned by means of a rod 34 which runs through the hollow shaft 29 and has its upper end fixed to the disc 33 in any suitable manner. The disc 33 carries a number of pins 35^a the purpose of which will appear below. The lower end of the rod 34 carries a crank arm 35 with an upwardly extending end which engages a bar 36 which may be shifted a slight distance until a projection 37 engages a pin or other stop 38 whereby the disc 33 may from time to time be given a slight movement for a purpose that will appear below. 10 20 The ratchet 28 has one set of teeth 39 which engage the pins 26 and 27 and another set of teeth 40 which engage the corresponding teeth on a spool 41 which turns freely on the shaft 29. This spool 41 has a second set of ratchet teeth 42 which engage corresponding ratchet teeth on the bottom of a rewinding spool 43 which also turns freely on the spindle 29. A cord 44 which passes over a pulley 45 to a weight 46 is wound one way on the spool 41 and a second cord 47 is wound the opposite way on the spool 43. The cord 47 is brought out to any suitable position and preferably near the handle 36 so that it may be grasped and drawn to rewind the cord 44 from time to time, as desired. 25 30 35

The spool 41 has an arm 48 extending therefrom and fixed thereto which at first runs horizontally and then vertically to support a figure 49 above the level of the top of the table 7 and this table has a circular opening 50 so that a slot is formed between the edge of this opening and the edge of the disc 32 for permitting the rod 48 to pass completely round the spindle 29. The parts are so arranged and disposed that when a ball 20 falls on the flap 23 and depresses the same and elevates the counter-weight 28^a the ratchet 28 turns through ninety degrees and when it so turns it engages a small pivoted contact 51, 52, 53 or 54, according to its location. 54 represents the home plate, 51 first base, 52 second base and 53 third base. As soon as the wire 48 engages one of these pivoted contacts, this contact is thrown on its pivot 55 so that the pivoted contact 51 engages a fixed contact 51^a or the pivoted contact 52 engages a fixed contact 52^a or the movable contact 53 engages a fixed contact 53^a or the movable contact 54 engages a fixed contact 54^a and remains in engagement until all movable contacts are restored to their normal positions by means of the pins 35 on the disc 33 40 45 50 55 60 65 70 75 80 85 90 95 100 105 110 115 120 125 130 which function by shifting the rod 36

which has been described above. It will be understood that the pivots 55 and the fixed contacts 51^a, 52^a, 53^a, and 54^a are mounted on the fixed disc 32.

There is also a rod 56 which runs the length of the apparatus and is mounted in suitable bearings so that it may be turned through substantially ninety degrees and it is provided with two lugs 57 and 58, as shown in Figure 7, and these parts are so arranged and disposed that when thrown, as shown in said figure, the rod 48, and of course the runner 49 which is attached thereto, are both imprisoned at home plate and in the other sections, not shown, it will be understood that the lugs 57 will prevent any other rod 48 from reaching the home plate.

By a reference to Figure 4, the electrical connections will be readily understood. The disc 32 is shown with the fixed contacts 51^a, 52^a, 53^a, and 54^a and the movable contacts 51, 52, 53 and 54, all of these movable contacts being pivoted on their respective pivots 55 which rise from the disc 32, as above described.

The movable contact 51 has a wire 59 that runs to a lamp 60 in a suitable box 61 with a glass front 62 in which are mounted these lamps and the glass front has certain signs, such as "First base," "Second base," "Third base," "Home plate," so that when a lamp is illuminated the sign will show the base to which it is connected. A wire 63 runs from the lamp 60 to a battery or other source of supply 64 and this battery is also connected to a wire 65, at its opposite pole which is connected through a series of wires 66 with the fixed contact 51^a as well as the other fixed contacts 52^a, 53^a and 54^a.

The movable contact 52 is similarly connected to its lamp 67 by means of a wire 68 and the other terminus of this lamp is connected to the wire 63 and in a similar manner the movable contact 53 is connected by a wire 69 to its lamp 70 which in turn is connected to the lead in wire 63 and the last lamp 71 is connected to the movable contact 54 by means of a suitable wire 72.

It will also be noted that the movable contact 54 has the wire 72 extended to a hand switch 73 and thence the wire 74 which runs from its hand switch to the bell 75 and a wire 76 runs to the wire 66 so that when the contacts 54 and 73 are closed the bell 75 will ring.

In the foregoing, the rod 56, bar 36 and string 47 are shown as connected to one section only of the apparatus. It is to be understood that these parts are connected to each section exactly as shown for the first section so that all sections may be governed by these three controls and operate simultaneously.

In view of the foregoing, the operation of

my improved amusement apparatus will be readily understood. Assuming that several sections are together under one attendant and several people are playing the game at the same time the action is as follows. Each strikes his lever 3 at the handle 10 as vigorously or as softly as he desires. If he hits too hard, the ball 20 will pass by both of the guides 21 and 22 and if he does not hit hard enough this ball will not reach the guides and in either event the ball just falls back on the lever 13 and returns to its initial position. If, however, the player should use more care and hits the lever just right, he can land the ball between the guides 21 and 22 so that the ball will rest on the flap 23 for a moment, then lower the flap before falling on the lever 13 and returning to its initial position. As soon as the flap 23 is lowered, the spindle 24 is turned, the escapement operates to release the spool 41 under the influence of the weight 46 and permit the same to turn through ninety degrees. This permits the arm 48 to swing through ninety degrees and as it swings it strikes its movable contact 51 and thereby closes a circuit, which indicates first base on the sign. This swinging of the contact 51 frees the same from the rod 48 and allows this rod to move again as soon as the escapement functions once more, as above described, and then the rod 48 will reach the contact 53 which functions precisely as did the contact 51 so that then the light is illuminated for second base just as the light for first base was illuminated when the contact 51 was swung. In a similar manner a further action of the escapement produced, as above described, will allow the rod to reach third base and throw the contact 53 for the purpose of closing the circuit through the lamp 70 and thereby indicating that third base has been reached. A game is continued so that when another release occurs, the contact 54 is shifted and then all lights are illuminated through the circuits above described. That instant the attendant turns the rod 56 so as to secure the rod 48 in place, closes the switch 73 to sound the bell and let all know that the game is over and he pulls the string 47 to rewind the weights 46 and shoves the rod 36 to open all the contacts and extinguish all the lights and then he opens the switch 73 and turns the rod 56 and the game is ready to be played on over again. The one who first gets his runner to home plate wins the game. To further simulate the game of baseball, the top of the disc 32 has a baseball diamond 77 indicated thereon so that both of the lights and by this diamond 77 a player can see how his man 49 is progressing and know how near he is to the finish, it being understood that the lamps in the box 16 are placed in a convenient line as at the top and rear of the apparatus

where they may be readily viewed. The box 16 with the ball 20 is also placed where it can be clearly seen so that at all times all the necessary parts of the apparatus may be viewed by the player so that he can determine at once what is doing and the results he obtains, whereby his interest is intense and his skill important.

While I have shown and described one embodiment of my invention, it is obvious that it is not restricted thereto, but that it is broad enough to cover all structures that come within the scope of the annexed claims.

Having thus described my invention, what I claim is:

1. In an apparatus of the class described, means for projecting a ball, means for catching said ball, an escapement connected to said ball catching means and a figure and mounting connected to said escapement at all times and means for driving said mounting, the parts being so arranged and disposed that when the ball catching apparatus functions the figure may be shifted.

2. In an apparatus of the class described, means for projecting a ball and means for catching the same, a figure and means for mounting and driving the same, means connected to the ball catching mechanism for releasing the said mounting and driving means when the ball catching means functions, a reset for restoring the figure to its initial position and a set of visual signals connected to said reset means.

3. In an apparatus of the class described, means for projecting a ball and means for catching the same, an escapement and means connecting the same with the ball catching means, whereby the escapement will be released when the ball catching means functions, a figure constantly connected to the escapement and means for mounting and driving the same subject to the control of said escapement and a diamond adjacent to said figure.

4. In an apparatus of the class described, means for projecting and means for catching a ball, an escapement connected to said ball catching means and made to function when the ball catching means functions and a figure and means for mounting and driving the same connected to said escapement and subject to be released by the escapement and means for locking the figure in place upon its return to substantially its initial position.

5. In an apparatus of the class described, means for projecting a ball and means for catching the same, an escapement connected to said ball catching means, a figure and a mounting and driving means subject to the control of the escapement and an audible electric signal with circuit closing means actuated by the figure at a predetermined point in its course.

6. In an apparatus of the class described, means for projecting and means for catching a ball, an escapement connected to said ball catching means at all times, a figure and means for mounting and driving the same subject to the control of said escapement, a baseball diamond, a lock adapted to hold said figure at the home plate, and means for driving the figure.
- 10 7. In an apparatus of the class described, means for projecting and means for catching a ball, an escapement connected to said ball catching means, a figure and means for mounting and driving the same subject to the control of said escapement, a baseball diamond and an audible electric signal with circuit closing means actuated by the figure at a predetermined point in its course.
- 15 8. In an apparatus of the class described, means for projecting and means for catching a ball, a figure and means for mounting and means for driving the same subject to the action of the ball catching means; a lock adapted to hold the figure in its initial position and a set of visual signs indicating the position of the figure in the apparatus after leaving its initial position.
9. In an apparatus of the class described, a figure and means for mounting and driving the same, a series of visual signs with means connecting them with said figure, whereby the position of the figure will be indicated by the signs and a reset mechanism for resetting the apparatus so that the signs will cease to function after the reset mechanism is actuated.
- 10 10. In an apparatus of the class described, an escapement and means for actuating the same, a figure and means for mounting and driving the same subject to the control of the escapement, visual signs for indicating the position of the figure and a reset means connected with the signs, whereby the signs may be made inoperative.
- 15 11. In an apparatus of the class described, an escapement and means for actuating the same, a figure and means for mounting and driving the same subject to the action of the escapement, a diamond, a reset apparatus and signs connected with said reset apparatus.

In testimony whereof, I have hereunto set my hand this 21st day of March, 1923.

ERNEST O. NORBERG.
